UNITED STATES PATENT OFFICE.

CHARLES L. HUSTON, OF COATESVILLE, PENNSYLVANIA.

TRANSFER SYSTEM FOR HEAVY METAL PLATES.

Application filed February 2, 1923. Serial No. 616,563.

My invention relates to systems of interacting carriers by which heavy plate material may be shifted and transferred for convenient operation upon it by shears or other tools.

My main purpose is to present a complete system of handling heavy metal plates, including the transfer of the plates from a transfer table to a carrier and delivery by it to a pair of opposed shears, not only maintaining the plates in alignment and definite relationship of the angles between the ends and the sides of the plates, but also progressively feeding them for successive operations of guillotine shears or other heavy duty tools concurrently upon opposite sides of the plates.

Also for adjusting the distances between the shearing planes and for relieving the plates from binding of the shear knives.

In this system I have provided cooperating feed tables which may extend in the same direction or at an angle to each other for delivery by the one table and transfer by the other and structure for maintaining the alignment of the parts and for intermittently progressing the plates between the operations.

I reduce the number of settings required, eliminate the hand labor and much of the care required in setting the plate and avoid the loss of time previously lost in clamping, thus securing great rapidity in work.

The maintenance of the alignment automatically by mechanical means and the step by step feeding and cutting also help to increase the speed. Cutting upon both sides at the same time secures uniformity, and adjustability of the shears toward and from each other makes my invention suitable for all widths of plate.

I also provide auxiliary movements and devices so as to carry out the successive cuts and operations necessary to the desired object in a mechanical, practical manner for rapid production of steel plates by avoiding the necessity for turning the plates around as is usually done for shearing successively the opposite sides of the plate with the accompanying repeated adjustment and danger of shifting or creeping from its position during the process of shearing.

My invention thus not only obviates troublesome and tedious hand work but more reliably secures parallel, straight and ac-

curately sheared product, with definite relative angles between the ends and sides obtaining a better result at a more rapid rate and lower cost. Moreover it fits in with modern methods of rapid production already applied in other parts of the operations involved between the rolling of the plate and the finished product.

I have preferred to illustrate my invention by one main form only, with several different adjunctive devices, selecting a form which is practical, efficient and reliable and which at the same time well illustrates the principles of my invention.

Figure 1 is a top plan view, largely diagrammatic, showing the preferred form of my invention.

Figure 2 is an enlarged top plan view differing slightly in detail of the elements shown but otherwise corresponding to Figure 1.

Figure 3 is an end elevation of a portion of the structure seen in Figure 2.

Figure 4 is a perspective view of a pair of shears suitable for carrying out my invention.

Figure 5 is a diagrammatic view showing hydraulic means of synchronization.

Figure 6 is a section of one of the carrier elements shown in Figures 2 and 3.

Figure 7 is a top plan view of the fine adjustment used.

Figure 8 is a side elevation, partly sectioned, of Figure 7.

Figure 9 is a top plan view of an alternative form of magnetic drag which may be used.

Figure 10 is a fragmentary side elevation partly in longitudinal section of the structure seen in Figure 9.

Figure 11 is a fragmentary end elevation of the structure of Figures 9 and 10.

Figures 12, 13, 14, 15, 16, 17, 18 and 19 are top plan views intended to be largely diagrammatic illustrating some of the different arrangements of tables and cooperating structures with which my invention may be used.

Figures 20 and 21 are elevations largely diagrammatic of the form seen in Figure 18.

Figures 22 and 23 are elevations largely diagrammatic showing an overhead drag conveyor.

In the drawings similar numerals indicate like parts.

My invention is intended to cooperate with any table construction and layout, of which I have shown diagrammatically in Figures 1-2 and 12-19 various different types. These 5 represent a few only among the many installations to which my invention may be applied. I have given greater detail in Figures 1, 2 and 3 than in the other figures.

In Figures 1-3 roller table 10 feeds the 10 plates from the mill to a cut-off shear 11 at which one end, or, if necessary, both ends of the plate may be cut. From this shear the plate passes to the shear table 12 by which it may be fed lengthwise by rollers 13 and 14 operating in unison to a second cut-off shear 11 if shear 11 has been used to cut one 15 end only. In either event the plate may be turned in a horizontal plane by operation of the two sets of reversely placed rollers 13 and 14 in opposite directions. The plate is 20 subsequently transferred from this shear table to the left in the figure by cooperating transfer tables 17 and 18.

In Figures 1-3 the table 17 is made up of 25 a number of roller-supporting fixed sections 19, 19', 19², 19³, 19⁴ and table 18 comprises a corresponding number of rocking sections 20, 20', 20², 20³, 20⁴, here shown as five in 30 number, so as to transfer the plate to operating mechanism or to a point of further distribution.

The rollers of the fixed sections are suitably driven by mechanism not shown. The sections 20-20⁴ are adapted to tilt about a 35 common shaft 21 which is located near the right hand end of the sections. Their rollers are driven by a motor 22 through suitable gearing shown including gears 23 at the motor and gears 24, 24' and 25, 25' upon 40 parallel shafts 26, 21. The gear 26 through two connected idlers 27, 27' drives intermeshing gears 28 upon and between the transfer rollers 29. As thus described the transfer rollers are effective to move the 45 plate in either direction, intended to be toward the left in Figures 1 and 2. This mechanism so far described is old.

The transfer table is tilted by thrust rods 30, one for each section, pivotally connected 50 to the section at one end and with a beam 31 at the other. The beam is common to the lifting mechanism for all of the sections and is lifted by the plunger of a hydraulic cylinder 32 located at an intermediate point with 55 respect to the sections.

As will be recognized by those familiar with the art I have shown in Figures 1, 2 and 3 a part only of the transfer table, which may comprise as many sections or sets of 60 sections as may be desired for the duty intended.

At any suitable intervals along the length of the beam 31, transverse beams 33 are located, preferably one at each end of a section served by beam 31. These beams 33

rest upon and turn in piers 34. They carry beams 35 at a distance from their pivotal points selected with a view to getting the desired amount of lift for rollers 36 desirably located not further apart than one for 70 each section of the transfer table. Beneath the points at which these rollers 36 are to be located bearings 37 are formed to which are pivoted thrust rods 38 connected at their upper ends at 39 to heads 40 which slide in 75 guides 41 and carry the rollers 36 at their upper ends; with the purpose and effect that the lifting of the left hand end of the transfer table will not lift its rollers alone but will lift other rollers spaced from the end 80 of the transfer table to any predetermined extent.

The guides 41 are formed in the upper faces of roller-supporting frames parallel 85 to guide channels 43. These latter lie approximately in line beneath the left hand end of the tilting transfer table and, in the form shown, are cut away to allow the ends 90 of the transfer table sections to drop to the position shown.

The fixed and tilting sections of the transfer table are well suited to supply the means of transfer from roller tables out of line with the shear or other tool to be served. Though part of the mechanism described 95 above is my invention, in its broadest aspects the invention is independent of the character of transfer means and even of the need or existence of such transfer means (as seen in Figures 14 and 15); and the transfer mechanism seen in Figures 12 and 13, as well as any transfer mechanism claimed by me in conjunction with my broader invention may be the same or different from that shown in Figures 1, 2 and 3. It is my intention to 100 claim the broader subject matter, independently of whether the roller table from the mill and the shear or other heavy duty mechanism to be served be in line or not, and, if not in line, independently of whether they 105 be parallel or not.

The roller-supporting frames extend at an angle—here at a right angle—to the transfer table where one is used, but may, as seen in Figures 14 and 15 be directly in line 115 with the roller (feed) table. These frames are intended to support plates by their rollers while the plates are being conveyed to a guillotine shear or other heavy duty (usually but not necessarily hydraulic) mechanism for operations upon the sides of the plates.

As will hereafter more fully appear the greatest utility of my invention is secured in feeding and controlling the plates for 125 concurrent shearing operations upon opposite sides of the plates though part of the advantage may be secured even when one side only of the plate is operated upon or when the operation is by other heavy duty 130

tools, such as punches, instead of or supplemental to shears.

The frames extend to any distance desired and may serve a plurality of tools. In Figure 1 they are shown as broken away near the middle of the view and near the farther end to indicate that in the omitted portions any other desired mechanism may be applied to feed into or receive from a carrier, 10 hereinafter described, with which the roller frames are intended to cooperate, or to operate upon the plates carried. The frames are shown as passing through between guillotine shears 44, 45 which are oppositely placed, 15 facing each other and are intended to be opposite counterparts except that both cut progressively in the same direction with respect to the observer. Both are adjustable toward and from each other by means of screws 20 46 which are connected to turn together so that the knives are automatically parallel and at the same time the cutting planes are equally distanced from the sides of the roller-supporting guide channels or frames. 25 I have preferred to show the guillotine shears as hydraulic. As shown, their pairs of cylinders 47, 48 are supplied with fluid under pressure through pipes 49, 50 and branches 49', 50', 50''. The pipes are connected with balanced high pressure cylinders 51, 52 of the same steam intensifier. 30

Further detail of the shears selected for my illustration will be given in connection with Figure 4, showing one form of shear 35 which is suitable for this use, and with Figure 5 illustrating hydraulic means for synchronizing the shears. As the shears enter into the claims of the present application broadly rather than specifically and 40 there are many ways by which the functions of the shears may be performed, of necessity I have restricted my illustration of them and show in diagrammatic and perspective one shear and two means of synchronizing the 45 movement within the shear only. Without intending to restrict to hydraulic operation I would refer to my applications copending herewith for simultaneous intensifier feed for separate shears, Ser. No. 576,999, and 50 facing shears for cutting heavy metal plates Ser. No. 576,998, both filed July 24, 1922, as giving further detail and other means of synchronizing the form preferred by me when hydraulic pressure is used. 55

The frames carry rollers 53 and 54 which support the plate freely after it has been rested upon them by depression of the transfer table.

Between the frames is located a carrier 60 guide 55 of general U section whose base 56 rests upon the same beams 57 as afford support to the frame members.

The upper part of the guide member is flanged at 58 on each side to give lateral 65 guiding support to a carrier grip or clutch

59, traveling upon the guiding surface 60 and dragged in either direction by the cables 61, of which one cable is attached to an ear upon one grip or clutch and the others pass through it to serve other grips or clutches. 70

The cables 61 pass from the clutch direct or about one of idlers 62, to one of tension take-up idlers 63, thence along the bottom of the guide channel over one of the idlers 64, 65 or 66, a different one for each independent grip or clutch member, to and about a motor-driven drum 67, about idlers 64', 65' or 66', as the case may be, about one of the idlers 63' and back to the corresponding one of the several grips or clutches so that each grip or clutch will be capable of separate operation in either direction by a distinct cable and drum. 75

The effective connecting means by which the grips or clutches engage the plates to hold or drag them, selected for illustration here, is electromagnetic and two forms of electromagnets are illustrated from among the many by which this feature might be shown. They are illustrative only, and the broader features of my invention are independent of the character of the grips or clutches as well as of the electromagnetic principle upon which they operate, though the electromagnetic form offers many advantages not possessed by other forms. 80

I will describe the form shown in Figures 1-3 and 6-8 first:

The electromagnets 68 are free to raise and lower with the casing of the grips or clutches but are restrained (by the top of the casing through which they pass) against longitudinal movement with respect to the casing. The electro-magnets are connected selectively by trolley arms 69 with different conductors 70, where it is desirable to control their energization separately; otherwise with a common conductor only, so that the energization of these conductors may be utilized to cause the magnets to engage with the plates or disengage from them, whether the casings are being moved along the guides or not. When the electro-magnets are energized and are covered by a plate they will engage the plate to drag it or hold it. 100

These electro-magnetic drags, as the entire individual mechanisms may be called, will follow any inequalities in the plate by lifting to maintain engagement with it and may be used separately and independently to convey different plates at the same or at different speeds, or to convey one or more plates while holding one or more others. 105

The movement of the plates provides for getting the next plate ready while another plate is being operated upon or transferred from operating position, after it has been operated upon. Any number or arrangement of drags may be used and a plurality of drags may be used upon a single plate to 110 115 120 125 130

maintain the plate in alignment and to give additional strength of grip or hold for the movement of the plate.

In conjunction with my apparatus shown 5 I have illustrated a fine adjustment (also preferably electromagnetic in its gripping action) for shifting the plates laterally, by movement of the different devices shown in the same direction at the same time, or for 10 aligning a plate, in the form of screw-operated feeds. These are grouped in the different figures in sets of two or three devices located between the sections of the transfer table where a lateral transfer is shown, or 15 at the sides of a roller table or drag conveyor. Obviously they may be used wherever convenient. This fine adjustment is not my invention but cooperates nicely with it in the exactness of setting of the plate which 20 may be secured.

The fine-adjustment devices grip the plates by electro-magnetic cores which may correspond generally to the ones already described as forming part of the drag feed, 25 but require much shorter extent of movement and need not rely upon trolley engagement to secure their magnetizing current, obtaining it from any suitable source by means of conductors 71. The magnetic cores 30 are shown at 72 and move between guides 73. They are provided with rigid nuts 74 to receive threaded shafts 75 rotated through gearing at 76, 77 from motors 78. As the devices are separate and distinct, the electro- 35 magnets forming the grips may be energized to cause them to engage with a plate and may be fed in the same direction to adjust the plate either way in its entirety or may be used separately or together to turn and 40 adjust the plate in a horizontal plane. One of them may hold the plate, acting as a pivot about which the plate is turned by another. Like the drag-conveyor magnets the magnet grips lie below the lower level 45 of the plates when not energized and lift to engaging contact when energized. Elsewhere, however, I show clutch devices operating above the plates.

In Figures 9, 10 and 11 I have shown another form of electromagnetic grip, suitable for either the drag conveyor use (with the cables of which it is illustrated) or with 50 any fine adjustment, including such translating devices as are seen in Figures 7 and 8. It can thus be used either to drag or to 55 adjust and align the plates.

In this form, Figures 9-11, the magnet casings 68' are rigid with the electromagnet cores 68². Their windings are protected and held in place by cover plates 68³. The casings are tapered at the edges and project at front and back where they are bored to receive tubular guiding projections 79 upon frames 79' to which the cables 61 or the fine 60 adjustment feeding devices are applied. The 65

frames are recessed to receive solenoid windings 80 for solenoidal armatures 80' whose upper ends 80² are of pin form and fit the interiors of the tubular extensions. These extensions are slotted to permit vertical movement of cross bars 81 carried by the pins, operating to lift the casings when the solenoids are energized and to permit them to lower when the solenoids are de-energized. The electrical connections shown 70 are such as to energize the solenoids and the main magnet windings when the trolley arms 69' are energized (or when any suitable switch is thrown, if used for the fine adjustments). 75

In Figure 4 I have illustrated a pair of guillotine shears suitable for carrying out my invention and will proceed to describe them, with the statement, however, that these shears are more completely described and 80 claimed in the above noted application for facing shears for cutting heavy metal plates.

The guide plates 82 provide ways upon or in which the bases 83, 83' of the shears are adapted to travel when the right-and-left-hand screws 84 are rotated within the nuts 85, 85' by means of any source of power or gearing connection with gears upon these screws. Slack can be taken up between the 90 nuts and the screws by moving one of the 95 nuts toward the other and fine adjustment can be made by moving both of the nuts in the same direction with respect to the base of either shear. This is done by set screws 86 in flanges 87 and bearing against 100 the sides of the nuts.

The power selected for the illustration of the guillotine shears is hydraulic and the two shears are duplicates in all respects except that, as set, they cut progressively in 105 the same direction. They will therefore be described in similar language with the use of the same reference characters applied to each.

The hydraulic pressure is applied to the 110 cylinders through jointed pipe sections 88 which maintain fluid connection uninterruptedly notwithstanding the movement of the shears.

The lower beams are shown at 89 supporting fixed knives 90 and angularly placed scrap cutting knives 91 connected therewith. The upper or movable beams 92 carry movable knives 93. These are connected with co-operating movable scrap cutting knives which do not show in this view. The movable beams are hung by pivotally connected links 94 from the forward ends of rocker arms 95 which are rigid with a pivot shaft 96. The rocker arms are connected with the 115 pistons of the operating cylinders by means of links 97. This secures synchronism of 120 the two sides of each shear.

The movable beams are returned to their 125 positions by the pull-back cylinders 98 whose 130

plungers 99 are connected by cross beams 100 from which rods 101 extend to the movable beams. The usual fluid connections from any suitable accumulator for the pull-back 5 are shown at 102.

The movable beams do not rest directly against the housings 103 but are set off from the housings so as to tend to fall toward them by gravity and are separated from them by 10 wedges 104 pivotally connected to levers 105. These levers center at 106 and are pivoted at their opposite ends to rods 107. The rods are connected at their lower ends by cranks 108 with shafts 109 supported in bearings in 15 the housings or frames. These are adapted to be carried by mechanism not here shown but described in detail in the application referred to above for facing shears for cutting heavy metal plates. There are two rods and 20 two pairs of wedges and connections, one at each side of each pair of shears.

By these means the wedges may be forced downwardly to bring the knives into the cutting planes and are retained in this position 25 as guides for the beams during the cutting, after which the wedges are withdrawn and the beams fall back by gravity, withdrawing the knives from the cutting planes for the upward stroke. This is of special importance 30 where cutting takes place on both sides of a plate and where for this reason the plate is not free to yield to relieve the friction between it and the upper knives on the upward stroke of the latter.

35 The upper surface of each lower beam is provided with openings for plate-supporting rollers 110. These rollers are lifted and lowered by crank arms 111, one for each shear, upon one of the same shafts 109 used 40 for operating the wedges. The crank arms connect through thrust strips 112 connected at their upper ends by one end each of these bell cranks to the arms 115 of bell cranks 116. The other arms 45 117 of the bell cranks carry the rollers 110.

As fully explained in the application above referred to, the operation of these parts is so timed that the rollers 110 are lowered prior to the cutting and are lifted after the cutting 50 operation and before the upward stroke of the movable knives. The upper beams are at the same time allowed to fall away from the cutting planes.

In order to provide for use of a single 55 shear only where hydraulic synchronism of the two ends of each shear is relied upon, and to permit the operation of a single shear only where one of the shears may be out of commission, I show by-passes 118 in Figure 60 5 between pipes 49³ and 50³ and between pipes 49⁴ and 50⁴ respectively, placing control valves 119 in the by-pass and control valves 119' and 119² in the piping beyond the by-passes. One of the valves 119', 119² will 65 be open and the other closed in each set when

by-pass valve 119 is open. When by-pass valve 119 is closed both of the valves 119' and 119² in each set will be open.

In operation of the construction thus far described, the plate is passed from the mill 70 to the shears which trim the ends, and when the ends have been trimmed it is passed by transfer tables to the drag conveyor. Its position is adjusted nicely with respect to this conveyor by the fine adjusting devices, 75 both to place it centrally and to give it perfect alignment so that the drag conveyor will carry it to the shears or other tools in exact alignment for the first operation and will control its position and advancement with 80 respect to the tools by successive movements.

The transfer tables by their tilting movement and by their rollers moving in planes laterally to the drag conveyor facilitate fine adjustment of the position of the plate and 85 alignment of the plate, both because they make it possible to support the plate above the drag conveyor while this is being done and because the direction of movement of their rollers greatly reduces the strain required to move the plate.

When the plate has been placed in approximate position the fine adjustment is given by the screw-operated electromagnetic 90 grips 59 or 59'. During this lateral shifting 95 or turning the plate is preferably supported above the rollers of the drag conveyor (which rotate in planes parallel to its length) upon transversely rotating rollers, such as those of a transverse table or independent plunger-supported rollers, such as 36'.

The electromagnets can be used either as stationary pivots about which the plate is turned or can be moved in either direction to 105 give rotation in the planes of the plate or bodily movement.

As soon as the fine adjustment and alignment have been completed, the plate is lowered upon the rollers preferably of the drag 110 conveyor, whose electromagnetic grips can be set against the plate before it is lowered or afterward as preferred.

It will usually be desirable to engage the plate by separate grips near its ends in 115 order to maintain the alignment reliably. The plate is then fed to the shear or other tool and as it approaches the shear it rises upon the shear rollers 110, lifted to protect the knives, without releasing the electromagnetic holds of the grips, which are so constructed as to lift with the plate and maintain their hold even when the rollers 110 of the shear are in raised position. The grips continue to maintain their holds during the shearing operation, ready for subsequent transfer without new positioning.

Prior to the operation of the shears the rollers 110 are lowered, resting the plate 130 upon the lower shear knives, where the plate

is held against side movement by the grips of the drag feed. After the shear has operated and its movable knives have lifted to allow further movement of the plate, the 5 rollers 110 are against lifted and the drag conveyor is operated to advance the plate ready for another cut, successive cutting operations being effected concurrently upon opposite sides until the full length of the plate 10 has been sheared. The same or other drag conveyor elements will then be available to advance the sheared plate to the position for another operation upon one or both of its sides, such as a punching operation, or to deliver it to loading tables or other destination. 15 Where a tapered plate is to be sheared, for example, one shear only need be operated.

I have carried the operation through with one mechanism in order to avoid confusion 20 and to complete the description of a preferred form before referring to other means by which much the same advantage can be secured, but have intended this preferred form to be suggestive only, indicating one 25 construction by which the desired functions can be carried out. Without any attempt at completeness I have shown a few of the modifications and changes in the mechanism which can be made, in Figures 12-23 illustrating the breadth of my invention and the 30 fact that both the character and relative location of the transfer mechanism used and the operating tools applied can be greatly changed.

35 For example, the transfer laterally, where used, need not be a plurality of transfer devices, but by one single transfer 18 as in Figures 12 and 13 where the plate is trimmed at the ends by oppositely facing shears, in 40 one form, back to back and in the other face to face. The manipulating rollers 13', 14' are shown in Figure 12 as lying on both sides of the pair of shears and in Figure 13 as between the shears. The roller table 10³ 45 in Figure 13 is assisted by casters 10⁴. Fine adjustments are shown in each and in each the plate is delivered to roller table 10², and carried by it to be weighed and finally for loading. The directions of motion of the 50 plate are indicated in these figures, as in the other figures by arrows.

In Figures 14 and 15 I have shown the plates as feeding directly (i. e., without lateral movement) from the mill through end-cutting shears, a single shear 11' in Figure 55 14 and oppositely facing shears 11' in Figure 15, to manipulating rollers 13', 14' and thence to a drag conveyor and a roller table 10². Fine adjustments are shown on opposite sides of the rollers 13', 14' and also on opposite sides of the rollers 13', 14' and also on opposite sides of the drag conveyor to indicate that adjustment may be made at either or both of these points as occasion may require. 60 Rollers 36 in the drag conveyor and

single rollers 36', all capable of being lifted are provided, the latter located opposite the rollers 13', 14'. They facilitate lateral movement and also alignment.

In Figure 16 two laterally directed roller 70 tables 17, 18 are provided between the roller table 10³ and the drag conveyor, with an intermediate pair of end-cutting shears 44', 45' corresponding generally to shears 44, 45 and adapted to be set for predetermined end 75 lengths. They cut concurrently, as do shears 44 and 45. Fine adjustments are located adjacent the roller table 10³ with a view to accurate alignment of the plates for operation upon them by the end-cutting-to-size shears. 80 I contemplate using accurate transfer tables at 18 to carry the plates which have been trimmed to length over to the drag conveyor so as not to require resetting and enable them to be gripped by the drag conveyor in perfect alignment and carried through the side cutting shears; exercising every care to secure the mechanical accuracy of the carriers or conveyors used, to maintain an alignment 85 which has been secured whether the carriers or conveyors engage the plate beneath its surface or, as in some of the later figures, above its surface.

It will be noted that the end cutting shears do not require scrap cutting knives as they are intended to take the entire width at each end at one stroke.

In Figure 17 I have indicated a reversal 95 of direction of movement of the plate, to show that this direction is not controlling, and have effected the transfer of the plate by an overhead crane having electromagnetic gripping devices engaging the upper surfaces of the plate, cutting the sides of the plate first by successive strokes, concurrently 105 on the two sides, maintaining the alignment by the crane and cutting the ends of the plate last.

Because of the difference in direction of feed, fine adjusting devices for grips or 110 clutches diagrammatically illustrated at 59 are interspersed between the rollers of table 10⁵ to adjust and align the plate preliminarily to its engagement by the drag conveyor clutches 59. These carry it through the shears 44, 45 and bring it in line beneath the rails 111 of the overhead crane 112. The crane is provided with a pair of gripping magnets 113 capable of independent or concurrent excitation and suspended by connections 114 from shives 115 raised and lowered by suitable drum and motor mechanism not shown by means of chains 116. The gripping devices are intended also to be capable of independent or concurrent movement, both vertically and along the length of the crane beam. The grips 113 can thus be moved toward or from each other to accommodate different lengths of plate so that the 115 crane will pick up the plate from its posi- 120 125 130

tion on the drag conveyor, maintaining its alignment, and carry it bodily into position for shearing by the end-cutting-to-size shears 44', 45' where it is cut concurrently at the two ends and from which it is passed by roller tables 10³ and 10' to weighing scales and loading devices. Obviously more than one crane 112 will be used where the widths of plates to be handled give trouble by tilting when lifted by the grips of a single crane.

In Figure 18 the construction shown is similar to that in Figure 17, but the fine feed grips 59 are located adjacent the roller tables 15 10⁵ to provide for the opposite direction of plate movement from that of Figure 17 and preliminary shears 11' are provided to cut up a plate (which has been rolled in multiple lengths) into approximately the lengths desired before it reaches the end-cutting-to-size shears 44', 45'. In this case the overhead crane and grips take the plate which has been cut to length and carry it to the drag conveyor, maintaining its alignment 25 until it has been engaged by the grips of the drag conveyor.

In Figure 19, overhead conveyors having two directions of travel are used, the one for lateral movement of the plate and the other 30 for longitudinal movement.

A shear 11' is provided where multiple lengths are rolled and the plate may be fed directly to the end-cutting-to-size shears 44', 45' or to the side of such shears as preferred. In the figure the plate is delivered at the side by roller table 10' and upon roller table 10³. Fine adjusting and aligning devices can be used either at this point or where the plate is deposited for shearing and 40 I have shown them in both places. The crane 112 picks up the plate at the left, if it be delivered at the side and carries it to the end-cutting-to-size shears to be cut, or engages it after it has been placed, as the 45 case may be; and the crane preferably retains its hold upon the plate and hence retains alignment while the ends of the plate are being sheared.

The plate is then carried from the end 50 shearing position over to a position in line longitudinally with the side cutting shears where it may be deposited for engagement by the longitudinally movable cranes 112', of which any number may be used, though 55 but two are shown. I show grips 59 in position between the rollers of roller table 10⁵ for use where it is desired to maintain hold upon the plate during the shift from one crane support to the other. Ordinarily these 60 grips 59 need not be movable for adjustment or alignment but may be given such movement if desired.

A roller table 10³ transfers the cut plate after the final operation.

65 The cranes 112' may have but one or

more than one gripping device each, according to the widths of plates to be handled, but preferably have two each in order to maintain the plate in horizontal position; and may retain their holds upon the plate 70 during the progress of the plate through the side cutting shears to ensure and maintain alignment.

In order to secure accurate alignment of the two ends of the overhead crane the supporting wheels 117, 117' of the crane on opposite sides may be geared together if desired.

In Figures 22 and 23 I show a different form of overhead gripping mechanism in 80 which a beam 118 is supported so that its flanges 119 extend longitudinally with respect to the movement of the plate. Wheels 120 of the carriages 121 ride upon the flanges 119. The carriages support a crane 85 beam 122 from which are suspended grips 113' by chains 116', passing over drums 123 driven through worm and worm wheel connection from a common shaft 124 connected with a motor 125. Clutch mechanism may 90 be interposed to raise or lower either grip independently.

It will thus be evident that all of the devices shown by me are capable of wide variation to accomplish the objects which I 95 have outlined; and it is my purpose to cover herein such modifications and changes as will naturally occur to those skilled in the art in view of my disclosure herein and which come within the reasonable spirit and 100 scope of my invention.

Having thus described my invention, what I claim as new and desire to secure by Letters Patent is:—

1. The method of handling and shearing 105 a sheet of heavy plate using a conveyor and oppositely facing heavy duty vertical movable shears which consists in centering and aligning the plate in position to be engaged by the conveyor, engaging and holding it 110 by the conveyor at a plurality of points and feeding it between the shears spaced to the desired distance to operate concurrently on both sides of the plate, operating upon the plate concurrently by the shears while the 115 conveyor maintains its hold upon the plate to maintain alignment and successively advancing the plate by the conveyor and operating upon it by the shears.

2. The method of handling and operating 120 upon a sheet of heavy plate from a mill by a conveyor and reciprocating tools on opposite sides thereof which consists in transferring the plate from the mill to the conveyor, aligning and centering the plate at 125 the conveyor and before the conveyor is engaged with the plate, engaging and holding the plate by the conveyor and transferring it thereby to the tools so spaced as to operate concurrently upon opposite sides of the 130

plate, at the same time maintaining its alignment, operating upon a portion of the two sides of the plate concurrently by the tools, lifting the plate with respect to the tools while maintaining hold by the conveyor, shifting the plate forwardly into position for a second operation of the tools, lowering the plate and repeating the operation upon the sides of the plate.

10 3. The method of handling and shearing a sheet of heavy plate by a conveyor and facing reciprocating shears which consists in centering and aligning the plate in position to be engaged by the conveyor, engaging and holding by the conveyor at a plurality of points, feeding the plate between the shears spaced to the desired distance to operate concurrently on both sides of the plate, operating upon the plate by the shears 15 concurrently and successively advancing the plate by the conveyor and operating upon it by the shears.

4. The method of handling by mechanism and shearing heavy metal plate by shears 20 having reciprocating knives which consists in transferring the plate to a position above the lower knives of the shears so spaced as to operate upon the plate concurrently upon opposite sides, lowering the plate upon the 25 knives of the shears, operating upon the plate by the knives concurrently on both sides, lifting the plate free from the lower knives of the shears, advancing the plate into position for a succeeding cut and lowering the plate and then cutting it by the shears, while maintaining the position of the plate by the hold of the transfer mechanism.

5. The method of handling and shearing 30 a heavy metal plate by the use of a conveyor and facing shears having reciprocating knives which consists in transferring the plate by the conveyor while maintaining hold upon the plate with vertical movement 35 of the plate into a position above the lower knives of the oppositely facing shears, lowering the plate upon the knives, cutting the plate concurrently upon opposite sides, concurrently cutting off the scrap, shifting the 40 movable upper knives of the shears away from the plate and lifting them, lifting the plate to a position free from the lower shear knives while maintaining the conveyor hold, advancing the plate into position for a succeeding cut, lowering the plate upon the lower shear knives and repeating the operation.

6. The method of handling and shearing a sheet of heavy plate by the use of a conveyor, facing shears having reciprocating knives and lifting rollers which consists in transferring the plate by a conveyor while maintaining hold upon the plate with vertical movement of the plate into a position above 45 the lower knives of the oppositely facing

shears, lowering the plate upon the shears, cutting the plate concurrently upon opposite sides, concurrently cutting off the scrap, lifting the plate by the rollers to a position free from the shear knives, advancing the plate into position for a succeeding cut, lowering the plate upon the shear knives and repeating the operation.

7. The method of handling from a mill and shearing a heavy metal plate, by facing 75 shears having reciprocating knives, which consists in feeding said plate from the mill, aligning the plate with respect to the cutting planes of the shear knives, feeding the plate between the shears placed so as to face 80 oppositely and spaced to the desired distance to cut on both sides of the plate, operating the shears synchronously to take cuts concurrently upon opposite sides of the plate, advancing the plate while maintaining its 85 alignment and repeating the shearing operation.

8. The method of handling from a mill and shearing a sheet of heavy plate by facing shears having reciprocating knives, which 90 consists in feeding said plate from the mill, aligning it with respect to the cutting planes of the shear knives, feeding it between the facing shears spaced to the desired distance to cut on both sides of the plate, operating 95 the shears synchronously to take cuts concurrently upon opposite sides of the plate and at the end of the cut cutting off the scrap, advancing the plate while maintaining the alignment and subsequently repeating 100 the shearing operation.

9. The method of handling heavy plate from a transfer table to shears by means of a conveyor and trimming the sides of the plate, which consists in placing the shears in 105 position opposite each other with their cutting planes at right angles to the direction of movement of the transfer table, adjusting the shears to the desired width of plate to be cut, carrying the plate by the transfer 110 table to a position in line with the shear knives while supporting the plate in a raised position above the conveyor, lowering the plate upon the conveyor, engaging and holding the plate by the conveyor at widely separated points for transfer by the conveyor so as to maintain the alignment of the plate, transferring the plate by the conveyor to the shears, taking an initial cut by both of the shears and advancing the plate by the 115 conveyor to a new plate position at which a succeeding cut is taken by the shears.

10. The method of handling heavy plate from a transfer table to two shears having reciprocating knives, by means of a conveyor, and trimming the sides of the plate, which consists in placing the shears in position opposite each other with their cutting planes at right angles to the direction of movement of the transfer table, adjusting 120

the shears to the desired width of plate to be cut, carrying the plate to a position in line with the shear knives while maintaining it in relatively raised position, lowering the plate to deposit it upon the conveyor, engaging and holding the plate by the conveyor at widely separated points for transfer by the conveyor so as to maintain the alignment of the plate and transferring the plate by the conveyor to the shears.

11. The method of holding heavy plate and of cutting it by shears, which consists in bringing the plate into alignment with the shears, in feeding the plate, in concurrently shearing both sides of the plate and in subsequently feeding the plate into position for a second cut on both sides while constantly maintaining its alignment with the shears.

12. The method of holding and cutting heavy plate, which consists in bringing the plate into alignment with the shears, in feeding the plate to the shears, in concurrently shearing both sides of the plate and at the end of the cut cutting off the scrap, thereby freeing the plate to move forward and in subsequently feeding the plate into position for a second cut on both sides while constantly maintaining its alignment.

13. The method of feeding heavy metal plate by mechanism and of cutting it by reciprocating shears, which consists in progressively and recurrently cutting both sides of the plate simultaneously, stopping the plate for each cut, feeding the plate between the cuts and holding it both while feeding and while cutting by the feeding mechanism.

14. The method of feeding heavy metal plate by mechanism and of cutting it by reciprocating shears, which consists in progressively and recurrently cutting both sides of the plate simultaneously, lifting the plate after each cut, feeding it between the cuts and maintaining the hold of the feeding mechanism throughout the operations.

15. The method of cutting heavy metal plate by reciprocating shears, which consists in progressively and recurrently feeding the plate, cutting both sides of it simultaneously, stopping the plate for each cut, and mechanically maintaining the alignment of the plate during the successive feedings for the cuts and during the cutting operations.

16. The method of shearing heavy metal plate by two shears having reciprocating knives operated by hydraulic cylinders fed from other cylinders which consists in placing the two shears in opposite positions to operate upon opposite sides of the plate, adjusting their distance of separation to correspond with the intended width of the plate, feeding the plate between the shears lengthwise of the shear knives while maintaining their alignment by the grip and guide of the feed and synchronizing the cutting process by supplying the cylinders

of the two shears with fluid from different cylinders of the same source of pressure to cause them to cut simultaneously upon the plate.

17. The method of shearing plates of heavy metal by hydraulic shears fed from separate cylinders, which consists in placing the shears in opposite positions to operate upon opposite sides of the plate, adjusting their distance of separation to correspond with the intended width of the plate, feeding the plate between the shears lengthwise of the shear knives while maintaining their alignment by the grip and guide of the feed, and synchronizing the method by supplying the operating cylinders of the two shears with fluid from different cylinders of the same source of pressure to cause them to cut simultaneously upon the plate, advancing the plate while guiding it to maintain its alignment and subsequently cutting the plate by the two shears in line with the first cuts.

18. The method of handling heavy metal plates upon tables by a conveyor and operating upon them by heavy duty reciprocating tools which consists in transferring the plates into approximate alignment with the conveyor, aligning the plates at the conveyor, gripping the plates and transferring them into position for concurrent operation at opposite edges by oppositely facing reciprocating tools and operating upon the two edges concurrently while the conveyor retains its hold upon the plates.

19. The method of handling heavy metal plates upon tables by a conveyor and operating upon them by oppositely facing heavy duty reciprocating tools which consists in transferring the plates into approximate alignment with the conveyor, aligning the plates at the conveyor, engaging and holding the plates by means of the conveyor and transferring them into position for concurrent operation at opposite edges by the oppositely facing reciprocating tools, operating upon the two sides concurrently while the conveyor retains its hold upon the plates, advancing the plates by the conveyor into position for a second operation by the tools and operating upon the plate in the new position, retaining the alignment by the conveyor between operations.

20. The method of handling heavy metal plates upon tables by a conveyor and operating upon them by end shears and oppositely facing heavy duty reciprocating tools which consists in transferring the plates upon the tables through shears, trimming the ends by the shears, transferring the plates in the same general direction of their lengths from the shears into approximate alignment and position for engagement by the conveyor moving in the general direction of movement of the plate, aligning and ad-

- justing the plate, engaging and holding the plate by the conveyor, transferring the plate by the conveyor into a position between heavy duty tools and operating upon it by the tools 5 while holding it by the conveyor.
21. The method of handling a heavy metal plate upon tables by a conveyor and operating upon it by end trimming shears and oppositely facing concurrent reciprocating shears with progression of the plate lengthwise between the shears which consists in carrying the plate to the end-trimming shears, trimming the ends by trimming shears, transferring the plate lengthwise from the shears into approximate alignment and position for engagement by a conveyor having movement lengthwise of the plate, aligning and positioning the plate, engaging and holding the plate by 10 the conveyor, carrying the plate by the conveyor between the reciprocating shears, operating upon it on opposite sides by the shears while holding it by the conveyor and advancing the plate by the conveyor into 15 position for a second operation by the shears.
22. The method of handling heavy metal plate and operating upon it by oppositely placed reciprocating shears to shear the ends and edges, which consists in transferring the plate to a lengthwise position between the shears for edge cutting, interrupting the progress at an intermediate point to align, shearing the ends by the 20 shears, operating the shears concurrently, and maintaining the alignment while transferring the plate to and operating upon its sides by the edge-cutting shears and between successive cuts of these shears.
23. The method of conveyor handling heavy metal plates and shearing at the ends and edges of the plates by reciprocating shears to size perpendicularly to each other, which consists in transferring the plate from 25 the mill into position for operation along opposite edges by the shears spaced to size, aligning the plate in position for operation by the shears, operating concurrently upon the plate at opposite edges, transferring the 30 plate into position for engagement by a conveyor operating perpendicularly to the edges of the plate which have been cut, engaging and holding the plate by the conveyor, transferring the plate by the conveyor into position for operation upon the intermediate 35 opposite edges by shears placed so as to face oppositely and adjusted to size and concurrently cutting these intermediate opposite edges of the plate by the shears.
24. The method of conveyor handling heavy metal plate to cut to size and square the ends and sides of the plate by oppositely facing reciprocating shears, which consists in transferring the plate into position for operation along opposite edges, 40 spacing the shears to size, aligning the plate in position for engagement by the shears, operating concurrently upon the plate at the opposite edges, conveying the plate into position for engagement by a conveyor operating perpendicularly to the edges of the plate which have been cut, engaging and holding the plate by the conveyor, transferring the plate by the conveyor into position for operation upon the other opposite edges by other oppositely facing reciprocating shears spaced to size and concurrently cutting the intermediate opposite edges of the plate by the reciprocating shears, the cutting of one of the sets of opposite edges being by successive cuts concurrently upon the two edges and the alignment being maintained between the cuts by operation of the conveyor. 45
25. The method of conveyor handling heavy metal plate and cutting to size and squaring the ends and sides of the plate, which consists in feeding a plate into position for cutting opposite edges, aligning it, concurrently cutting the edges, carrying the plate parallel to the edges cut to an intermediate point by one conveyor, engaging the plate at the intermediate point by a second conveyor, carrying the plate at right angles to the edges cut by the second conveyor into position for cutting the intermediate opposite edges while maintaining its alignment and concurrently cutting these last named opposite edges. 50
26. The method of conveyor handling heavy metal plate and cutting and squaring the edges of the plate, which consists in feeding a plate into position for cutting opposite edges, aligning it, concurrently cutting the edges, carrying the plate by a conveyor parallel to the edges cut to an intermediate point, engaging the plate at the intermediate point and carrying it by the second conveyor at right angles to the edges cut into position for cutting the other opposite edges and concurrently cutting them while maintaining alignment, one of the cutting operations being performed step by step. 55
27. The method of conveyor handling heavy metal plate and cutting and squaring the edges of the plate, which consists in concurrently cutting opposite edges of a plate to size, transferring the plate by the conveyors at right angles to each other while maintaining its alignment and into position for cutting the other opposite edges of the plate and concurrently cutting said other opposite edges. 60
28. The method of conveyor handling heavy metal plate and cutting and squaring the edges of the plate by reciprocating shears which consists in concurrently cutting edges of a plate to size, lifting the plate from above and moving it into the line 65

of travel of conveying means movable at right angles to the first movement, carrying it by the said means between the shears and cutting the other edges of the plate by a 5 succession of concurrent strokes with intermediate step by step advance of the plate, maintaining alignment throughout.

29. A pair of oppositely placed reciprocating shears for heavy metal plate, adjusting devices for varying the distance between 10 the cutting planes of the shears and a feed for the plate adapted to grip the plate and to move it, guiding it and maintaining alignment and free to follow vertical movements 15 of the plate.

30. A pair of oppositely placed reciprocating shears for heavy metal plate, means for synchronizing the movement of the shears, adjusting devices for varying the distance 20 between the cutting planes of the shears and a feed for the plate, gripping the plate, moving and guiding it and maintaining alignment and capable of following the vertical movement of the plate while maintaining hold upon it.

31. A pair of oppositely placed facing reciprocating shears, in combination with conveying mechanism for the plate adapted to grip the plate and move it between the 30 shears, maintaining engagement with the plate during vertical movement of the plate, rollers adapted to lift the plate free from the lower knives of the shears during movement and means for lifting and lowering the 35 rollers between cuts of the shears.

32. A pair of oppositely placed facing reciprocating tools in combination with a conveyor for feeding the plate between the tools, rollers upon the conveyor adapted to 40 sustain the weight of the plate, grips for the conveyor adapted to follow the plate in vertical movement thereof and rollers adjacent the tools adapted to raise the plate free from the conveyor and from the tool bed during 45 movement.

33. A pair of oppositely placed facing reciprocating shears for heavy metal plate, adjustable toward and from each other, in combination with a carrier for the plate 50 holding the plate at spaced points along its length and adapted to drag it intermittently through between the shears for coincident operation by the shears upon its sides.

34. A pair of oppositely placed facing 55 hydraulic shears for heavy metal plate adjustable toward and from each other, in combination with a carrier for the plate holding the plate at spaced points along its length and adapted to drag it through between the shears for coincident operation by the shears upon its sides, and hydraulic synchronization for the shears.

35. A pair of oppositely placed facing reciprocating shears adapted for adjustment to vary the distance between their cutting

planes, in combination with synchronizing means for the shears and a feed for a heavy metal plate adapted to successively advance the plate after each cutting operation upon the sides of the plate.

70

36. A pair of oppositely placed facing reciprocating shears for heavy metal plate and means for synchronizing the movements of the shears, in combination with adjusting devices for varying the distances between the cutting planes of the shears and a feed for the plate, gripping the plate at points considerably separated along the length of the plate, guided in feed movement and maintained alignment at the same time and adapted to feed the plate successively between the times when the sides of the plate are operated upon by the shears.

75

37. A pair of oppositely placed facing reciprocating shears and synchronizing means for the shears, in combination with means for adjusting the distance between the cutting planes of the shears, a frame extending from a position outside of the shears to a position between the shear knives, 80 rollers in the frame adapted to support a plate and a carrier for the plate movable along the length of the frame and adapted to advance the plate successively after concurrent cuts upon the side of the plate by the shears.

85

38. A pair of oppositely facing synchronized reciprocating shears, in combination with means for adjusting the distance between the cutting planes of the shears, a drag carrier for heavy metal plate adapted to drag the plate between the shears, grips for the carrier, engaging the plate at points widely separated along the length of the plate, guides for the carrier, rollers for supporting the plate on opposite sides of the carrier and supporting means for the rollers.

90

39. A transfer table having feeding rollers, means for lifting and lowering one end of the transfer table, a frame across the end of the transfer table, rollers in the frame adapted to facilitate movement longitudinally of the frame, a carrier adjacent the frame adapted to move a heavy sheet metal plate longitudinally of the frame, rollers and supports therefor on the other side of the carrier from the transfer table, adapted to facilitate movement of the plate from the transfer table and connections between the transfer table, lifting and lowering means.

105

and the last-named rollers for lifting them concurrently to provide support for the plate until it is positioned over the carrier and to drop the transfer table and rollers out of the way during the operation of the carrier.

110

40. A transfer table having feeding rollers on the table, means for lifting and lowering one end of the table, rollers beyond the transfer table in the direction of the 120 carrier.

125

- delivery of the transfer table and having their axes parallel to those of the rollers of the transfer table, connections between the lifting and lowering means for the table and said rollers to lift the rollers when the adjoining end of the table is lifted and to lower the roller and table together, a frame adjacent the delivery end of the transfer table, parallel rows of rollers on said frame, having their axes at right angles to the axes of the table rollers, a guide within the frame extending longitudinally of the frame, a grip for a plate adapted to move in the guide and connections for dragging the grip with the plate along the guide to move the plate over the frame rollers.

41. In rolling mill equipment, a carrier adapted to move a plate in the direction of its longitudinal axis, means for delivering the plate to the carrier, aligning devices for the plate at the carrier and a pair of concurrently operating oppositely facing reciprocating shears operating upon the plate.

42. In rolling mill equipment, a roller table adapted to receive a plate from the mill, an end trimming reciprocating shear served by the roller table, adjusting and aligning devices adjacent to the shear, a carrier adapted to receive and move the plate in the direction of its longitudinal axis and oppositely facing concurrently operating reciprocating shears served by the carrier and on opposite sides of it.

43. In rolling mill equipment, a plurality of roller tables adapted to transfer a plate in the direction of its length, oppositely facing shears in the line of travel of the plate adapted to trim opposite ends of the plate, a conveyor adapted to continue the movement of the plate in the same direction, adjusting devices for accurately placing the plate with respect to the center line of the conveyor and concurrently operating oppositely facing shears on opposite sides of the conveyor to trim the intermediate edges of the plate.

44. In rolling mill equipment, a roller table, adjusting devices adjacent the roller table, transfer means for moving a plate laterally from the roller table, oppositely facing shears adjustable as to distance at an intermediate point in said transfer, adapted concurrently to trim the ends of the plate, transfer devices adapted to receive the plate and movable lengthwise of it and oppositely facing concurrently operating shears adjustable as to distance on opposite sides of the transfer devices and adapted to trim the sides of the plate.

45. In rolling mill equipment, a roller table adapted to receive a plate from the mill, oppositely facing concurrently operating shears adjustable as to distance in the line of travel of said plate, roller table provision for feeding the plate in the direction of its

length into position for operation by said shears, adjusting devices for accurately placing the plate with respect to the shears, two separate transfer devices, one laterally with respect to the plate and the other receiving the plate therefrom and transferring longitudinally of the plate and oppositely facing concurrently operating shears on opposite sides of the second transfer device, adjustable as to spacing and adapted to cut the sides of the plate.

46. In rolling mill equipment, a roller table, a shear for separating lengths of plate in the line of travel of the plate, adjusting devices adjacent the roller table, transfer means for moving the plate laterally from the roller table, oppositely facing shears adjustable in distance at an intermediate point in said transfer, adapted concurrently to trim the ends of the plate, transfer devices adapted to receive the plate and movable lengthwise of it and oppositely facing concurrently operating shears adjustable as to distance on opposite sides of the transfer devices and adapted to trim the sides of the plate.

47. In rolling mill equipment, a roller table adapted to receive a plate from the mill, oppositely facing concurrently operating shears adjustable as to distance located along in the line of travel of said plate, roller table provision for feeding the plate in the direction of its length into position for operation by said shears, adjusting devices for accurately placing the plate with respect to the shears, two separate transfer devices, one lateral with respect to the plate and the other receiving the plate therefrom and transferring longitudinally of the plate, each maintaining the setting of the plate, and oppositely facing concurrently operating shears on opposite sides of the second transfer device, adjustable as to spacing and adapted to cut the sides of the plate.

48. In rolling mill equipment, two pairs of oppositely facing concurrently operating reciprocating shears, having the knives of one pair at right angles to those of the other, each pair adjustable as to spacing, in combination with transfer means for supply of a heavy metal plate to one pair of said shears to cut along opposite edges thereof and co-operating transfer means receiving the plate from the first transfer means, operating at right angles thereto and delivering the plate to the second pair of shears for cutting the intermediate opposite edges.

49. In rolling mill equipment, a pair of oppositely facing concurrently operating reciprocating shears, in combination with overhead electro-magnetic lifting and conveying means for transferring a plate from said shears, an electromagnetic drag conveyor adapted to receive the plate from the overhead crane and transferring it at right

angles to the direction of movement of the crane and a second pair of oppositely facing concurrently operating reciprocating shears adjustable as to distance, at right angles to the first pair and on opposite sides of the drag conveyor.

50. In rolling mill equipment, two pairs of oppositely facing concurrently operating guillotine shears having the knives of one pair at right angles to those of the other, in combination with overhead carriers having their paths of movement passing between the respective shears of the two pairs and overlapping each other, each carrier positively gripping the plate to maintain its alignment.

51. In rolling mill equipment, two pairs of oppositely facing concurrently operating reciprocating shears having the knives of one pair at right angles to those of the other, in combination with overhead electro-mag-

netic lifting and conveying means, having paths of movement respectively passing between the shears of the two pairs and overlapping each other, whereby a plate can be transferred from one pair of shears to the other while it is maintained in alignment by the lifting devices of said means.

52. In rolling mill equipment, two pairs of oppositely facing concurrently operating reciprocating shears, in combination with overhead carriers, having electro-magnetic gripping devices for each of the pairs of shears, the paths of the carriers crossing each other, whereby a plate may be positively engaged by the electro-magnetic gripping devices and be transferred from one carrier to the other and from one pair of shears to the other and its alignment may be maintained.

CHARLES L. HUSTON.
